UNITED STATES PATENT OFFICE.

DAVID W. KENDALL, OF GRAND RAPIDS, MICHIGAN, ASSIGNOR TO THE
PHOENIX FURNITURE COMPANY, OF SAME PLACE.

DESIGN FOR A CHAIR.

SPECIFICATION forming part of Design No. 27,727, dated October 12, 1897.

Application filed July 24, 1897. Serial No. 645,871. Term of patent 3½ years.

To all whom it may concern:

Be it known that I, DAVID W. KENDALL, a citizen of the United States, residing at Grand Rapids, in the county of Kent and State of Michigan, have invented and produced a new and original Design for Chairs, of which the following is a specification, reference being had to the accompanying drawing, showing a part thereof.

10 The figure is a perspective of my chair which I deem sufficient to fully illustrate my design.

The leading feature of my design consists of a frame supported upon square legs B, 15 gracefully curved and properly braced with girths F, G, and I, vertically curved, broad oblong arms A, and a series of ornamentally-

turned spindles D on each side of the frame and extending from the girths F to the arms, and a gracefully-curved seat E and back C, 20 the arms forming broad shelves or ledges at the sides of the chair with braces on the front legs to support their outer edges, all substantially as shown.

What I claim as my design is—

25 The design for a chair substantially as shown and described.

Signed at Grand Rapids, Michigan, July 23, 1897.

DAVID W. KENDALL.

In presence of—

ANDREW ALLGIER,
ITHIEL J. CILLEY.
